UNITED STATES PATENT OFFICE.

JOHN HARDMAN, OF NEW YORK, N. Y., AND WILLIAM H. DUTTON, OF PHILADELPHIA, PENNSYLVANIA.

HARP-STOP FOR UPRIGHT PIANOS.

SPECIFICATION forming part of Letters Patent No. 339,170, dated April 6, 1886.

Application filed May 28, 1885. Serial No. 166,983. (No model.)

To all whom it may concern:

Be it known that we, the undersigned, JOHN HARDMAN, a citizen of the United States, residing at 215 West Fifty-Fourth street, city, 5 county, and State of New York, and WILLIAM H. DUTTON, a citizen of the United States, residing at No. 1115 Chestnut street, Philadelphia, in the county of Philadelphia and State of Pennsylvania, jointly have invented certain 10 new and useful Harp Stops for Upright Piano-Fortes, of which the following is a specification, reference being had therein to the accompanying drawings.

Our improvement, which we wish to designate 15 as the "harp-stop," relates to a novel use or employment of the soft-pedal element of upright piano-fortes, and includes the necessary apparatus and method for actuating the same.

Our invention embodies and has objectively 20 several important and distinct benefits to the instrument, because with this improvement, the fingering or touch being unavoidably light and the strength of the tones subdued, the truth and distinctness of the notes are not impaired. This feature will obviate or greatly 25 modify the annoyances from piano-forte practice, especially by students. The piano, furthermore, will remain much longer in tune, thereby avoiding a great part of that attendant 30 expense, besides prolonging the durability of the instrument itself.

Our improvement consists in so raising the soft-pedal rail of the piano by a hand-lever movement that all the hammers are simultaneously advanced toward and held at will in 35 uniform position near the strings, so that short and light blows only can be given, and when released again will by specific gravity fall back to their proper position of rest, our improvements embracing, also, the attachments and apparatus for effecting the results set forth, 40 while at the same time we do not change nor in any way interfere with the soft-pedal action or its attachments, which are retained as auxiliaries to our improvement. (See drawings.)

Figure I shows a front view of the upper part of a piano with the front broken away, showing our improvement in elevation. Figs. II and III represent the inside elevation of 45 the left-hand end of an upright piano-forte

with the peculiar contrivances for actuating our improvement as arranged with Hardman's combined action bracket *a*, the soft pedal and hammers being shown in their normal positions of rest at Fig. II and raised to a fixed 55 position for the short-stroke soft-pedal action against the wires at Fig. III. Figs. IV, V, and VI are enlarged views of certain parts. *b* shows the hammer-rest rail, to the left-hand end of which we secure a horizontal plate perforated by an elongated slot, as at *c*. Fig. V shows plan and end views of a steadyng or re-enforce bar, *d*, of metal, secured by slotted adjusting angle-plates *e* to the tops of the outer arms of the bracket *a*. They give firmness to and preserve the damper-rail in line 60 against warping, twisting, &c., so that when the rail is lowered its back side cushion takes against the bar and there rests, as shown in enlarged figure, VI.

In the last-named figure, VI, the hammer is represented in two positions, that on the left (see dotted lines) being in its normal state of rest, and that on the right in the position as raised and held for the harp-stop action near 75 to the strings *g*.

In our operating device, *h* shows the damper-rod of the instrument, connected, as usual, at its lower end with the lever of the foot "pedal," (not shown;) but in this case the rod is provided with a stop-cap, *x*, (see Fig. IV, end view,) to the center of which a strong vertical pin is secured, which pin, passing through the slot in the plate *c*, will as the rod *h* is moved up or down, cause the damper-rail *b*, and consequently the hammers, to rock forward or backward to the position desired. As an alternate the plate *c* may be simply perforated 80 to fit the pin, and the orifices below through the instrument may be elongated to admit the 85 rod itself to rock back and forth; but the preferred plan is that described.

The rod *h*, with our improvement, is almost exclusively actuated by hand by the following-described method: In the operating devices, *i* 95 represents a metal or plate sliding in battens, as shown, its upper end being turned horizontally, Figs. I, II, III, and IV, where the plate is widened and perforated or forked to receive and actuate the damper-rod *h* by the 100

collar *m*, secured to the rod above the top of the plate *i*, to hold the rod when lifted by the plate. Near the lower end of this actuating-plate *i* the strong pins are made fast to receive between them the operating-arm of a rocking lever-plate, *n*, which oscillates upon a fixed pin, as shown, the plate *n* being actuated by the left hand through the medium of the handle of a curved crank-plate, *p*, the motions of which are limited by stop-pins *o* *o*, to limit the movement of the crank in either direction when raising or depressing the lever-plate and its attachments.

In addition to the described mechanism for our harp-stop, we attach proper directions for actuating the same, placed upon or near the end of the key-board or upon the end block, but near to the actuating-crank *p*, for which we prefer an ornamental metal plate 20 with stamped raised letters and the words "Harp Stop" and figure of a harp raised thereon. It will be readily seen that by this device the hand must control the whole range of hammers, raising them all simultaneously to the line nearest the strings consistent with their action from the slightest touch, yet without at all interfering with the free action of the usual soft pedal when it is in use, as by the touch of the left hand upon the lever-crank the keys are 25 again released and with the damper-bar *b* drop back to the bar *d* at rest. This system insures the least possible percussion upon the strings, effecting great saving in the wear upon the striking-surface of the hammers, and prevents 30 beating of the strings out of tune.

We are aware that a soft-pedal device consisting of a movable rail provided with dampers to be interposed between the strings and hammers has been operated by both pedal 40 and hand stop, and make no claim to such construction.

What we claim, and desire to secure by Letters Patent, is—

1. In an upright piano-forte, the device for actuating the soft-pedal bar, consisting of the 45 hand-crank *p*, rock-plate *n*, sliding rod or plate *i*, and lifting-rod *h*, constructed, arranged, and actuated in the manner substantially as described.

2. In an upright piano-forte, the oscillating 50 soft-pedal bar *b*, the forked plate *i*, lifting-rod *h*, and a lifting device, as *p* *n*, connected to said forked plate, whereby the soft-pedal bar may be operated either by hand-crank or the ordinary pedal, substantially as described. 55

3. In an upright piano-forte, the following elements in combination: the hand-crank locking device *p*, lever *n*, the forked plate *i*, the lifting-rod *h*, having collar *m*, the re-enforce bar *d*, having plates *e*, support for said 60 re-enforce bar, and the soft-pedal bar *b*, having plates *e*, all constructed, arranged, and operating as shown and described.

4. In an upright piano-forte, the following elements in combination: the oscillating soft- 65 pedal bar *b*, perforated plate *e*, re-enforce bar *d*, damper lifting-rod *h*, actuating-lever *n*, and vertical plate or rod *i*, all arranged and operated as and for the uses described.

In testimony whereof we affix our signatures 70 in presence of two witnesses each.

JOHN HARDMAN.
WILLIAM H. DUTTON.
